United States Patent Office

Des. 176,275
Patented Dec. 6, 1955

176,275

TOASTER

Robert A. May, Wynnewood, Pa., assignor to Proctor
Electric Company, Philadelphia, Pa., a corporation of
Pennsylvania

Application December 15, 1954, Serial No. 33,567

Term of patent 14 years

(Cl. D81—10)

FIG.2.

FIG. 3.

FIG. 4.

FIG. 5.

Fig. 1 is a perspective view of a toaster embodying my new design;

Fig. 2 is a plan view of the same;

Fig. 3 is a side elevational view of the toaster; and

Figs. 4 and 5 are end elevational views of the toaster taken, respectively, from the opposite ends.

I claim:

The ornamental design for a toaster, substantially as shown.
